(57) **CLAIM**

The ornamental design for a tissue container having an interior reflective surface, as shown and described.

DESCRIPTION

FIG. 1 is a perspective view of a tissue container having an interior reflective surface showing our new design;

FIG. 2 is a front view thereof;

FIG. 3 is a rear view thereof;

FIG. 4 is a left side view thereof with the right side being a mirror image thereof;

FIG. 5 is a top view thereof;

FIG. 6 is a bottom view thereof; and,

FIG. 7 is a perspective view thereof with the container shown in an open position.

The broken lines shown in the figures are for illustrative environmental purposes only and form no part of the claimed design.
